United States Patent Office

Des. 220,288
Patented Mar. 23, 1971

220,288

PILLOW BLOCK

Norman Schweizer, 26—02 S. 7th W.,
Missoula, Mont. 59801

Filed Dec. 3, 1969, Ser. No. 20,341

Term of patent 14 years

Int. Cl. D15—05

U.S. Cl. D55—1

FIG. 1 is a perspective view of a pillow block showing my new design;

FIG. 2 is a top plan view thereof;

FIG. 3 is a front elevational view thereof;

FIG. 4 is a back elevational view thereof;

FIG. 5 is a left side elevational view thereof;

FIG. 6 is a right side elevational view thereof.

I claim:

The ornamental design for a pillow block, substantially as shown.
